Primary Examiner — Caron D Veynar*Assistant Examiner* — Martie K Holtje(74) *Attorney, Agent, or Firm* — Wiley Rein LLP**CLAIM**

The ornamental design for a glass door smoker, as shown and described.

DESCRIPTION

FIG. 1 is a top, right front perspective view of a glass door smoker showing my new design;

FIG. 2 is a front elevational view thereof;

FIG. 3 is a left side elevational view thereof;

FIG. 4 is a right side elevational view thereof; and,

FIG. 5 is a top plan view thereof.

The bottom and rear surfaces of the glass door smoker, not shown, form no part of the claimed design.
